DESIGN FOR A REVERSIBLE DRESS

Helen Lentini, New York, N. Y.

Application September 6, 1939, Serial No. 87,057

Term of patent 3½ years

To all whom it may concern:

Be it known that I, Helen Lentini, a citizen of the United States, and a resident of the city of New York, in the county of New York, and State of New York, have invented a new, original, and ornamental Design for a Reversible Dress, of which the following is a specification, reference being had to the accompanying drawing forming a part thereof.

Fig. 1 is a front view of a reversible dress showing my new design.

Fig. 2 is a rear view of the dress shown in Fig. 1.

I claim:

The ornamental design for a reversible dress substantially as shown.

HELEN LENTINI.
